By Wallace R. Lane

Attorney.

UNITED STATES PATENT OFFICE.

FRANCIS J. PLYM, OF NILES, MICHIGAN.

DESIGN FOR A WEATHER-STRIP FOR CASEMENT-OPENINGS.

51,509.

Specification for Design.

Patented Nov. 20, 1917.

Application filed June 9, 1916. Serial No. 102,771. Term of patent 3½ years.

To all whom it may concern:

Be it known that I, FRANCIS J. PLYM, a citizen of the United States, residing at Niles, in the county of Berrien and State of Michigan, have invented a new, original, and ornamental Design for Weather-Strips for Casement-Openings, of which the following is a specification, reference being made to the drawings forming a part thereof.

The figure illustrates a perspective view

of a weather strip for casement openings showing my new design.

I claim:

The ornamental design for a weather strip for casement openings, substantially as shown.

FRANCIS J. PLYM.

Witnesses:

H. R. LINN,
CHAS. H. ADAMS.
